A. G. F. KURCOWSKI

TYPEWRITING MACHINE

Filed Sept. 29, 1925

Patented July 26, 1927.

UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed September 29, 1925. Serial No. 59,254.

This invention relates to sound-deadening casings or cabinets for typewriting machines.

It is customary to provide such casings with a glass window at the top thereof, so as to render visible the work-sheet. However, owing to the reflectory nature of the glass, objectionable glare may be thrown in the eyes of the typist, thereby rendering the work-sheet invisible, and consequently defeating the purpose of the window.

Various expedients have been resorted to for preventing objectionable reflections from the surface of the glass to the eyes, such as, for instance, a blind or shield positionable upon the casing in such a manner as to intercept the rays of light directed at the glass. Said blind has been ordinarily built the full width of the opening, and, in order to intercept the rays of light which may obstruct the vision of the work-sheet, useful light is also intercepted, thereby rendering the inside of the cabinet dark, which is objectionable.

In this invention, means are provided whereby the glare-causing rays are intercepted, while, at the same time, the other rays of light illuminate the inside of the casing, thereby rendering visible the work-sheet.

In the present exemplification of the invention, there is provided a support movably mounted upon the casing and overlying the window. On the support there is adjustably mounted a glare-prevention shield, which may be positioned and set in any suitable position or region over the glass and thus nullify the bothersome rays of light only. Two or more shields may be used, depending upon the sources of light causing the glares.

Another feature of this invention relates to means for facilitating the cleaning of the typewriter types, without necessitating the withdrawal of the typewriter from the casing. In the Underwood machine, the types are pivotally mounted in an arcuate plate or sector and are thrown back into a type-basket at the front of the machine. The front plate of said Underwood machine is provided with an arcuate opening in front of the type-basket, and it is intended to provide the front wall of the casing with a similar opening and a hinged plate conforming

to the outline of the opening, thus providing a seal to prevent the emission of sound, while at the same time rendering the types accessible from the outside of the casing. The upper portion of the front wall of the casing partially overhangs the keyboard, and the hinged part of the plate includes a forward extension terminating in a hinge-eye swingably secured to a rod which bridges a recessed portion of the overhang. A novel latch holds the lower edge of the hinged plate to the adjacent front wall of the casing.

Other features and advantages will hereinafter appear.

In the accompanying drawing, Figure 1 is a side view, in elevation, of an Underwood sound-deadening casing having an Underwood typewriting machine placed therein, and shows the invention applied thereto.

Figure 2 is a front view, in elevation, of the same cabinet, having the invention applied thereto.

Figure 3 is a cross-sectional plan view, through the line 3—3 of Figure 2.

Figure 4 is a cross-sectional view, in elevation, through the line 4—4 of Figure 2.

There is in the market an Underwood sound-deadening casing for Underwood typewriting machines, and one of its objects is to deaden the noise arising from the operation of the machine. Said casing is diagrammatically illustrated in Figures 1 and 2, and is shown enclosing a typewriter 10 which, however, is not completely enclosed, but has a keyboard extension 11 protruding through an opening 12 in the front wall of the casing, to render the machine operable from the outside of the casing.

The casing includes a body-part 13 and a cover 14, the latter being pivotally mounted upon the former by means of hinges 15. At the top of the cover there is provided an opening 16 which is sealed against the emission of sound by means of a glass-plate 17 fitted into a recess 18 in the cover and secured thereto by means of clips 19. The purpose of the glass, is to render the work-sheet visible without necessitating the displacement of the cover.

In order to prevent reflections of the rays of light from striking the glass and from interfering with the comfortable reading of

the work-sheet, there are provided one or more glare-prevention or spot shields 20 rockably and slidably mounted upon a support or cross-bar 21 which is in turn rockably mounted upon studs 22 secured to brackets 23, the brackets, in turn, being fast to the cover 14 by means of screws 24. By means of the shields 20 it is possible to intercept bothersome rays of light which may 10 prevent the reading of the work-sheet, while at the same time permitting other rays of light to go through the glass and thus illuminate the interior of the casing, which is advantageous.

15 According to the present exemplification of this invention, two spot shields are shown but it is obvious that either one, or more than two, could be used to conform with lighting conditions in the room where the 20 machine is used. The shields are made of opaque material, such as sheet-metal, and are secured to hubs 25 by means of screws 26. The hubs 25 are provided with open slots 27 engaging with the bar 21 and are 25 held thereon by means of pointed screws 28 as shown in Figure 1. The screws 28 may have knurled heads 29 to facilitate their manual operation, thereby precluding the necessity of using tools to make adjustments.

30 The screws may be loosened to either rock the shields or to move them into any desired position along the bar, and each may be caused to swing to either position shown, or the bar may be swung and lowered to the 35 position shown in dot-and-dash lines, or lower if necessary, or the shields may be taken off when not required.

Since it is desired to simplify the manipulation of the shields as much as possible, so 40 that the operative may quickly adjust them to conform with the lighting conditions of the room, there are provided friction joints for the support 21. Said frame terminates with two side arms 30, each having a loop 45 31 at the end thereof, the loop encircling the studs 22. The ends of the studs, according to this invention, are threaded and have nuts 32 and lock-nuts 33 to hold cup-washers 34 under predetermined pressure.

50 Another feature of this invention relates to means for facilitating the cleaning of types 35, which are operated by keys 36, without necessitating the removal of the machine from the casing. The Underwood 55 machine is provided with an arcuate opening 37 conforming with the outline of the type-basket in front of the machine. Said opening is normally left uncovered when the machine is operated outside of the casing, but when in the casing, it is necessary to somehow cover the opening to prevent the emission of sound therethrough. In this invention, it is proposed to provide a plate 38 conforming with the outline of the opening 37 and to provide the plate with a hinge

39 fast thereto, or forming an integral part thereof, the hinge co-operating with a rod 40 embedded in slots 41 in an overhanging portion of the casing and secured thereto by means of screws 42. The hinge-portion of 70 the plate 38 extends forward from the body of the plate, as illustrated in Figures 1 and 3.

At the bottom, the plate 38 is provided with a snap-lock or catch 43 engaging with a groove 44 in the front wall 45 of the machine. Said lock may be secured to the plate 38 by means of screws 46 through a metal strip 47, which incidentally may serve as a means for securing a felt lining 48 to 80 prevent the emission of sound through the plate 38. The lock may consist of a resilient plate 49 conveniently formed into shape as shown.

It will be noted that the catch is backed 85 against the plate 38 by means of a rear extension 50, so as to prevent bending the comparatively thin detent 51 of the latch. The plate 49 is bent at 52, the bent portion engaging with the upper edge of the strip 47. 90

Variations may be resorted to within the scope of the invention, and portions of the improvements may be used without others.

Having thus described my invention, I 95 claim:

1. The combination with a sound-deadening casing for a typewriting machine, the casing having a glass window to render visible the platen of said machine, of a support extending along the window, and a glare-prevention shield overlying only a portion of said window, the shield being movable on said support from one region to another along said window, whereby glare-causing rays of light are prevented from striking the glass, while other rays of light are permitted to pass by said shield and through the glass to the interior of the casing.

2. The combination with a sound-deadening casing for a typewriting machine, the casing having a glass-sealed opening to render visible the platen of said machine, of a spot-shield overlying said opening, whereby objectionable rays of light, interfering with the visibility of the platen, may be intercepted by said shield previous to striking the glass, said spot-shield being rockably and slidably mounted upon a frame, the frame being in turn rockably mounted upon brackets on said casing.

3. The combination with a sound-deadening casing for a typewriting machine, the casing having a glass window to render visible the platen of said machine, of a support extending along the window, and a plurality of glare-prevention shields carried by the support and movable independently of one another from one region to another lengthwise of said window, to prevent glare-caus-

ing rays of light from striking the glass, while permitting other light to pass by said shields and through the glass to the interior of the casing.

5. The combination with a sound-deadening casing for a typewriting machine, the casing having a glass window to render visible the platen of said machine, of a support extending along the window, and a plurality of glare-prevention shields carried by the support and movable independently of one another from one region to another lengthwise of said window, to prevent glare-causing rays of light from striking the 10 glass, while permitting other light to pass by said shields and through the glass to the interior of the casing, said support being movable crosswise of said window to change the position of all of said shields, as a unit.

15. The combination with a sound-deadening casing for a typewriting machine, the casing having a glass-sealed opening to render visible the platen of said machine, of a spot-shield overlying said opening, and means for controlling the position of said spot-shield, said controlling means including a hub fast to the shield, the hub having an open slot to receive a cross-bar pivotally mounted on brackets on the casing, and 20 means for setting the shield in any desired position on said cross-bar.

6. The combination with a sound-deadening casing for a typewriting machine, the casing having a glass window, of a support 25 overlying the window, and a plurality of glare-prevention shields carried by the support and adjustable therealong to different angles with respect to one another.

7. The combination with a sound-deadening casing for a typewriting machine, the casing having a glass window, of a support adjacent the window, and a plurality of glare-prevention shields carried by the support and overlying only portions of said 30 window, the shields being adjustable to different angles relatively to one another and independently movable from one region to another along said window for preventing glare-causing light from striking the glass, 35 while permitting other light to pass between the shields, through the glass, and into the casing.

8. The combination with a sound-deadening casing, having a glass-sealed opening in the line of vision of the operative to permit the observance of printing upon a work-sheet in a typewriting machine enclosed therein, of means for preventing some of the rays of light from striking the glass, 40 said means including a plurality of spot-shields adjustably mounted upon a frame, which is in turn adjustably mounted upon brackets, borne by said casing.

9. The combination with a sound-deadening casing, having a glass-sealed opening in

the line of vision of the operative to permit the observance of printing upon a work-sheet in a typewriting machine enclosed therein, of means for preventing some of the rays of light from striking the glass, said 45 means being adjustable to conform with lighting conditions in the room in which the sound-deadening casing is used, said means including a plurality of circular plates rockably and slidably mounted upon a frame, 50 the frame, in turn, being rockably mounted upon the casing.

10. The combination with a sound-deadening casing for a typewriting machine, the casing having a glass window, of a support 55 overlying the window, and a plurality of glare-prevention shields carried by the support and adjustable therealong to different angles with respect to one another, said support being movable from one position to another across said window.

11. In combination, a sound-deadening casing for a front-strike typewriting machine having a type-basket in front thereof to facilitate the cleaning of the types, the front of said casing including a portion overhanging the keyboard and a wall therebeneath having an opening permitting access to the type-basket, and a door conforming with said opening, said door including a 60 forwardly-extending portion terminating in a hinge-eye mounted upon a rod extending across a recess in the overhanging portion, said recess forming a continuation of said opening, and the forwardly-extending portion of the door providing a closure for said recess.

12. In combination, a sound-deadening casing for a front-strike typewriting machine having a type-basket in front thereof to facilitate the cleaning of the types, the front of said casing including a portion overhanging the keyboard and a wall therebeneath having an opening permitting access to the type-basket, a door conforming with 65 said opening, said door including a forwardly-extending portion terminating in a hinge-eye mounted upon a rod extending across a recess in the overhanging portion, said recess forming a continuation of said opening, and the forwardly-extending portion of the door providing a closure for said recess, and a detent carried by said door adjacent the lower edge thereof, said detent including a resilient flat spring having its 70 free end provided with a catch, said detent also including a finger carried by said spring and arranged to bear against the rear face of the door, whereby to steady said spring, said wall of the casing having a depression into which the catch is projected to hold the door closed.

13. The combination with a sound-deadening casing for a front-strike typewriting machine having a type-basket in front there-

of to facilitate the cleaning of the types, and the front wall of said casing having an opening conforming with the outline of the type-basket, of means for closing said opening, said means including a plate rockably mounted upon a hinge secured to the front wall of the casing at the top thereof, and

means for resiliently locking the plate in its closed position, said last-mentioned means including a clip made of resilient material, said clip being secured to the plate and engaging with a detent forming an integral part of the front wall of the machine. 10

ALFRED G. F. KUROWSKI.
